UNITED STATES PATENT OFFICE.

JOSEPH L. HILLER, OF MATTAPoisETT, MASSACHUSETTS.

DESIGN FOR A HAMMER-MILL BEATER.

56,924.

Specification for Design.

Patented Jan. 18, 1921.

Application filed December 15, 1919. Serial No. 345,143. Term of patent 14 years.

To all whom it may concern:

Be it known that I, JOSEPH L. HILLER, a citizen of the United States, residing at Mattapoisett, in the county of Plymouth and State of Massachusetts, have invented a new, original, and ornamental Design for Hammer-Mill Beater, of which the following is a specification, reference being had to the accompanying drawing, forming part thereof.

The figure is a perspective view of the beater.

The material and essential features of the design reside in lending artistic harmony and grace to the central portion 1 having an eye 2, a thickened portion 3 which is symmetrical with the central portion, extends toward the eye end of the beater and termi-

nates in the shoulders 4. Another feature of distinction is in modeling the form to accommodate, without artistic offense the edge 5 and surface 6, which, when the beater is not in artistic use, perform certain functions of utility.

The design as a whole is graceful and presents an ornamental attractive shape and appearance.

I claim the ornamental design for hammer mill beater as shown and described.

In testimony whereof I have affixed my signature in the presence of two witnesses.

JOSEPH L. HILLER.
